ELECTRIC WALL PLATE OR THE LIKE

Gunther S. Grieshaber, Syracuse, N.Y., assignor to Pass & Seymour, Inc., Syracuse, N.Y., a corporation of New York

Filed June 6, 1961, Ser. No. 65,480

Term of patent 14 years

(Cl. D26—13)

FIG. 1

FIG. 2

FIG. 3

FIGURE 1 is a front elevational view of an electric wall plate or the like, embodying my new design;

FIGURE 2 is a side elevational view; and

FIGURE 3 is an end elevational view thereof.

The dominant features of my design reside in the portions shown in full lines, wherein the essential features include the depressed central panel with its characteristic longitudinally grooved ornamentation extending for substantially the full length of the plate between narrow transversely curved and elevated side panels showing sharp lines of demarcation at the junctions of the side and main panels.

I claim:

The ornamental design for an electric wall plate or the like, substantially as shown and described.
